(74) *Attorney, Agent, or Firm* — Edward S. Sherman

(57) **CLAIM**

The ornamental design for a roasting rack, as shown and described.

DESCRIPTION

FIG. 1 is a first perspective view of a roasting rack in a closed assembled state, showing my new design;

FIG. 2 is a second perspective view thereof, in an open and separated state;

FIG. 3 is a top plan view thereof in the closed assembled state;

FIG. 4 is a bottom plan view thereof;

FIG. 5 is a left side elevation view thereof, the right side elevation view being the mirror image thereof;

FIG. 6 is a front elevation thereof; and,

FIG. 7 is a back elevation view thereof.

The broken lines in FIGS. 1–7 are for illustrative purposes only, depicting the environment of the new design, and forming no part thereof as claimed.

1 Claim, 2 Drawing Sheets
